US00D710173S

(12) **United States Design Patent**
Frenken

(10) **Patent No.:** **US D710,173 S**
(45) **Date of Patent:** **** Aug. 5, 2014**

(54) **HAND-HELD POWER TOOL**

(71) Applicant: **Gustav Klauke GmbH**, Remscheid (DE)

(72) Inventor: **Egbert Frenken**, Heinsberg (DE)

(73) Assignee: **Gustav Klauke GmbH**, Remscheid (DE)

(**) Term: **14 Years**

(21) Appl. No.: **29/460,885**

(22) Filed: **Jul. 16, 2013**
